UNITED STATES PATENT OFFICE.

VERNON HOXIE, OF ADRIAN, MICHIGAN, ASSIGNOR TO LAMB WIRE FENCE CO., OF ADRIAN, MICHIGAN.

WEFT-MAGAZINE FOR WIRE-FENCE LOOMS.

SPECIFICATION forming part of Letters Patent No. 771,151, dated September 27, 1904.

Application filed January 25, 1904. Serial No. 190,582. (No model.)

To all whom it may concern:

Be it known that I, VERNON HOXIE, a citizen of the United States, residing at Adrian, in the county of Lenawee and State of Michigan, 5 have invented a new and useful Weft-Magazine for Wire-Fence Looms, of which the following is a specification.

This invention relates to certain improvements in machines or looms employed in the 10 manufacture of wire fences.

The principal object of the invention is to provide a magazine by which the picket or weft wires may be automatically fed to the mechanisms for applying the clips or other 15 securing devices by which they are secured to the longitudinal or warp strands.

A further object of the invention is to provide a magazine of such nature as to permit the feeding of the wires by gravity.

20 A still further object of the invention is to provide a magazine into which a large number of wires may be placed either automatically or by hand and allowed to feed by gravity or by means of suitable mechanism to a discharge-point, the wires being at all times in view of the operator, so that he may remove twisted and cut wires or, if necessary, straighten out any of the wires which may become crossed, it being possible to remedy any 25 defects long before the wires arrive at the discharge-point, so that it will be unnecessary for the operator to stop the machine.

30 A still further object of the invention is to provide a pick-up mechanism for controlling the discharge of the wires from the magazine, so that only a single wire may be discharged at each operation.

35 A still further object of the invention is to provide an automatic means for adjusting the wires longitudinally before their entrance to the dies, so that a proper length of wire may be left at each end for attachment to the salvage-wires.

40 With these and other objects in view, as will hereinafter more fully appear, the invention consists in the novel construction and arrangement of parts hereinafter described, illustrated

in the accompanying drawings, and particularly pointed out in the appended claims, it being understood that various changes in the 50 form, proportions, size, and minor details of the structure may be made without departing from the spirit or sacrificing any of the advantages of the invention.

In the accompanying drawings, Figure 1 is a 55 general perspective view illustrating a portion of a wire-fence loom provided with a magazine constructed in accordance with the invention. Fig. 2 is a transverse sectional elevation of the magazine. Fig. 3 is a side elevation of a portion of the mechanism, showing the means for controlling the feed of the wires from the magazine. Fig. 4 is a sectional elevation illustrating a slight modification of the 60 invention.

65 Similar numerals of reference are employed to indicate corresponding parts throughout the several figures of the drawings.

In wire-fence looms as usually constructed the cross strands or wefts are supplied one at 70 a time to the dies forming the tie or stay, and in most cases the wires are concealed until ready to be dropped in position, so that the operator of the machine cannot tell whether or not he has a weft for the next operation of 75 the machine, this doubt being occasioned by the possibility of a tangle in a bundle of wires or the failure of the feeding mechanism to assume proper position when the dies are open and ready to receive the wire. With a machine of this pattern it also frequently happens that only a portion of a weft is delivered—that is, a partial picket—which action may be occasioned by the same circumstances that would provide no wefts at all.

80 In carrying out the present invention one of the principal features of novelty resides in the employment of an open magazine—that is to say, a magazine in which the wefts are in full view of the operator, so that the latter can 85 readily remove any badly-twisted or broken strands or may straighten them long in advance of their arrival at the discharge end of the magazine.

In the drawings, 1 indicates the general framework of an ordinary form of wire-fence loom, and 2 the dies employed for bending the tie-wires or other connecting-clips around the 5 strands at the point of intersection. The several dies may be operated from a single shaft 3; but as this portion of the mechanism forms no part of the present invention further detailed description is unnecessary, and it will 10 be understood that the magazine, which forms the principal part of the invention, may be applied to any form of loom for the manufacture of wire fabric without departing from the invention.

15 The frame of the magazine is formed of end bars 4, that are connected by a plurality of angle-bars 5, that are spaced from each other and serve as supports for a number of pairs of inclined bars 6, and the spaces between these 20 bars constitute the magazine.

The upper ends of the bars are flared outwardly to form a widened mouth for the convenient introduction of the weft-wires and the space between the bars is but slightly greater 25 than the diameter of the wire to be fed, so that it will be practically impossible for two wires to become crossed while in the magazine. The distance between the end bars is slightly greater than the length of the strands 30 to be fed, so that the feeding of the wires will not be retarded by the friction between the ends of the wires and the end bars.

The wires may be introduced in the top of the magazine either by hand or by any automatic machinery which will first straighten 35 out the wire and then cut it into the proper lengths, and it will be observed that the top of the magazine is of such an open character that the operator facing the machine may instantaneously observe any inaccuracies in the feed 40 or broken or twisted strands and may readily remove the same in advance of the arrival of imperfect wires at the discharge end of the magazine.

45 At the bottom of the magazine is a horizontally-disposed shaft 8, carrying a number of disks 9, that are provided with equidistant grooves 10 of sufficient depth to receive a single wire, and these disks are so arranged 50 that in rotating they will pick up the lowermost wires and carry them one by one from the magazine. The wires move down the magazine by gravity and press against the peripheries or guards of the disks, and when 55 the alining notches of said disks come opposite the lowermost wire the latter will enter the notches and will be carried up above the level of the bottom of the magazine, the wires being held in the groove for a portion of the 60 circumference of the disks by means of curved fingers 12, that are secured to the upper reservoir-bars 6.

At one end of the shaft 8 is a suitable feeding means for imparting a step-by-step move-

ment, and in the present instance this mechanism is shown in the form of a ratchet-wheel 65 15, having teeth of a number equal to the number of grooves or notches 10 in the periphery of one of the disks. With the teeth of the ratchet-wheel engages a pawl 16, that 70 is connected by a pitman 17 to a small crank carried by the main operating-shaft 3.

At a point below the discharge end of the magazine is arranged a pair of inclined plates 75 18, with which the opposite ends of the wire-strands may come into contact as they fall from the feeding-disks, and these plates serve to adjust the wires longitudinally, so that there will be a sufficient length of wire to form the selvage-wrap at each side of the fabric. 80

In the operation of the device the wires are fed in any suitable manner to the magazine and pass by gravity to the discharge end thereof. At the discharge end the lowermost wire presses against the peripheries of the several 85 disks, and when one set of alined notches arrive at a point opposite the wire the latter will enter thereinto, and on the next movement of the disks the wire will be carried up under the guards 12 of the disks. As the disks continue 90 to rotate they will pick up the successive lowermost wires, and when the first wire has passed beyond the ends of the guard-plate it will fall into proper position to form a part 95 of the fabric. 95

When used in connection with some classes of looms, the wires may be allowed to fall directly to the tie-forming dies; but in other cases they may be sustained in an intermediate position, so that they may be more quickly introduced in proper position, and thus enable 100 the machine to work at greater speed. 100

It is obvious that the machine instead of being formed of spaced bars 6 may be formed 105 of translucent material, such as a pair of sheets of glass, or its upper face may be provided with a glass panel in order to display the contents of the magazine. In either case the wires will be open to the inspection of the operator, and one or both ends of such magazine will be 110 open in order to permit the operator to withdraw any twisted or broken strands. This construction is illustrated in Fig. 4, wherein 115 6' designates a pair of transparent plates through which the operator may observe the weft-wires. It is not essential that the lower plate be formed of glass, but in many cases it will be desirable to use a glass plate, so that by transmitted light-rays the contents of the 120 magazine may be more clearly seen. 120

In order to insure the delivery of the weft-wires from the notches 10, wires or strips 19 are arranged at intervals in the width of the loom in such manner as to force the wires positively from the notches and also to guide 125 the same to proper position.

It will be observed that the bars 5 are provided with slotted end portions, through which

pass securing-bolts 30, which enter the bars in frame 4. This permits the adjustment of the distance between the opposite sides of the magazine in order to accommodate wires of 5 different gage.

Having thus described the invention, what is claimed is—

1. A weft-magazine for wire-fence looms, comprising a pair of sets of obliquely-disposed 10 spaced bars arranged parallel with each other, said bars being spaced to permit the removal of imperfect wefts, a series of disks arranged at the bottom of the magazine, the disks having peripheral notches that extend in alinement 15 with each other throughout the series, and means for revolving said disks.

2. The combination in a weft-magazine for wire-fence looms, of a pair of sets of bars extending in a direction transverse of the loom, 20 and adjustable to vary the distance between them, a plurality of sets of cross-bars secured to said transverse bars and disposed in parallel relation to form a magazine, all of said 25 bars being spaced to permit the removal of imperfect wefts, a series of notched disks at the lower discharge end of the magazine, all of said disks being provided with peripheral notches that are disposed in alinement

throughout the series, and means for imparting a step-by-step movement to said disks. 30

3. In weft-magazines for wire-fence looms, a magazine having a bottom discharge, a plurality of sets of disks having notched peripheries for the reception of the wires, guards extending over a portion of the peripheries 35 of the disks and serving to hold the wires in position in the notches, and means for imparting a step-by-step rotative movement to said disks.

4. In a weft-magazine for wire-fence looms, 40 a magazine having a bottom discharge, a plurality of sets of notched disks for receiving the wires from the magazine, a combined stripper and wire-guide arranged adjacent to the disks and serving to remove the successive 45 wires from the notches and to guide them to proper position, and means for imparting a step-by-step rotative movement to said disks.

In testimony that I claim the foregoing as my own I have hereto affixed my signature in 50 the presence of two witnesses.

VERNON HOXIE.
